B. Hestness.

UNITED STATES PATENT OFFICE.

BERNT HESTNESS, OF ROCKFORD, WASHINGTON, ASSIGNOR OF ONE-HALF TO I. J. BLAKKAN,
OF ROCKFORD, WASHINGTON.

FRUIT-PICKER.

No. 873,234.

Specification of Letters Patent.

Patented Dec. 10, 1907.

Application filed May 20, 1907. Serial No. 374,615.

To all whom it may concern:

Be it known that I, BERNT HESTNESS, a citizen of the United States, residing at Rockford, in the county of Spokane and State of Washington, have invented certain new and useful Improvements in Fruit-Pickers; and I do declare the following to be a full, clear, and exact description of the invention, such as will enable others skilled in the art to which it appertains to make and use the same.

My invention has relation to new and useful improvements in fruit pickers, and has for its object the production of a simple and economical device of this character by means of which fruit, such as apples, pears or the like, may be gathered or picked in a convenient and expeditious manner and with a minimum of labor.

With this and other objects in view, the invention consists of certain novel features of construction, combination and arrangement of parts, as will be more fully described and particularly pointed out in the appended claims.

In the accompanying drawings,—Figure 1 is a perspective view of my invention; Fig. 2 is a central longitudinal sectional view of my invention; Fig. 3 is a cross-sectional view on the line 3—3 of Fig. 2. Fig. 4 is a detail view of a spring and plate for closing the mouth of the lower chute section.

Referring now more particularly to the drawings, the numeral 1 represents the pole 35 of my improved fruit picker, which is provided near its lower end with a suitable handle 2.

The numeral 3 represents an extension rod which works in a corresponding socket 4 in the upper part of said pole, and is provided at its extreme upper end with a pair of scissors 5 composing two cutting members 6, provided with cutting blades 7 at their inner ends and terminating at their outer or opposite ends in suitable arms or handles 8, one of said cutting members being fixed and the other pivoted to said extension rod 3.

The numeral 9 represents a spring which works between the arms or handles of said cutting members 6 and serves to normally hold the cutting blade 7 of the pivoted cutting member 6 away from the cutting blade of the stationary cutting member.

The numeral 10 represents a suitable flexible, which is attached at its upper end by

suitable means near the outer end of the arm or handle of the pivoted cutting member, passes inwardly over a pulley 11 journaled in a suitable bearing 12, fixed near the outer end of the arm or handle of the stationary cutting member, and thence downwardly through the eye of an adjusting guide screw 13 working in a longitudinal slot 14 in the upper part of said pole 1. The lower end of said flexible 10 is provided with a number of loops 15 arranged at suitable distances apart and adapted to engage in the outer end of an arm 16 extending at right angles from the inner end of a turning member 17 journaled to a stub axle 18 extending outwardly from said pole 1 adjacent the lower end of its longitudinal slot 14, said turning member terminating at its outer end in a knob or handle 19, by means of which it may be easily turned. Said extension rod may be adjusted to different heights by pushing the same upwardly by means of said adjusting guide screw 13 and turning the body of said screw in one of a number of corresponding notches 20 cut in said pole at one side of said slot 14. 80

The numeral 21 represents a chute which is composed of a lower and upper chute section 22 and 23, respectively, said lower section being arranged longitudinally of and secured to said pole by one or more U-shaped 85 straps or plates 24, and said upper section being secured near the upper end of said extension rod and adapted to work in said lower section. (See Fig. 2).

A band or ring 25 is secured around said lower chute section and is provided with a suitable number of downwardly extending springs 26 adapted to press in against the outer face of said lower chute section and check the fall of apples or other fruit when falling through the same. A spring 27 is arranged in the lower end of said lower chute section and has hinged to one side a transverse plate 28, the purpose of which will be shown. 100

In the operation of my invention the extension rod 3 is adjusted to the proper height when it is retained in position by turning the body of said adjusting guide screw in one of the notches 20 of said pole, and the stem of the apple, pear, or other fruit to be picked inserted between the cutting blades 7 of said cutting member 6. The operator then takes hold of the knob or handle 19 of said turning member 17 and swings over the end of said 110

arm 16 downwardly, which arm, through the medium of said flexible 10 swings the arm or handle of said pivoted cutting member inwardly and cuts the stem of the apple or 5 other fruit, which falls into said chute 21, said downwardly extending springs 26 of said band 25 serving to check the fall of the same to prevent it from becoming bruised or otherwise damaged. To allow the fruit to fall 10 from the chute it is only necessary that the operator press the ends of said spring 27 sufficiently outward to allow said plate 28 to swing open.

The numeral 29 represents a band or ring 15 which fits around the upper end of said pole 1 and prevents the extension rod 3 from falling out of the socket therein. To remove said extension rod from said pole it is only necessary to remove said retaining band or ring 29.

20 From the foregoing description, taken in connection with the accompanying drawings, the construction and operation of the invention will be readily understood without requiring a more extended explanation.

25 Various changes in the form, proportion and the minor details of construction may be resorted to without departing from the principle or sacrificing any of the advantages of this invention.

30 Having described my invention, what I claim as new and desire to secure by Letters Patent, is:—

1. In a fruit picker, the combination of a pole, an extension rod working in one end of 35 the pole, a lower chute section arranged longitudinally of, and sustained by the pole, an upper chute section sustained by the extension rod, and working in the lower chute section, and an annular ring arranged to encircle 40 the lower chute section, said ring having a plurality of resilient spaced springs adapted to embrace said section.

2. In a fruit picker, the combination of a pole, an extension rod adjustably secured in 45 one end of said pole, a lower chute section ar-

ranged longitudinally of and secured to said pole, an upper chute section arranged longitudinally of said extension rod and working in said lower chute section, an annular ring working around said lower chute section and provided at its lower end with a number of longitudinally disposed springs, with means secured in the lower end of said lower section for normally closing the same against the passage of fruit. 55

3. In a fruit picker, the combination of a pole having a longitudinal socket in one end, with a longitudinal slot opening through the wall thereof, one of the walls of the slot being provided with a plurality of spaced 60 notches, an extension rod working in the socket, and means secured near the inner end of said rod for engaging either of said notches.

4. In a fruit picker, the combination of a pole having a longitudinal socket in one end with a longitudinal slot opening through the wall thereof, one of the side walls of the slot being provided with a plurality of spaced notches, an extension rod working in the 70 socket and a guide member arranged near the inner end of the extension rod, extending through said slot, and adapted to engage either of said notches.

5. In a fruit gatherer, the combination of a pole having a longitudinal socket in one end, and a longitudinal slot provided at one edge with a number of notches and communicating with said socket, and means secured near the lower end of said extension rod and 80 adapted to engage in one of the notches of said longitudinal slot of said pole.

In testimony whereof I have hereunto set my hand in presence of two subscribing witnesses.

BERNT HESTNESS.
